UNITED STATES PATENT OFFICE

MELVIN L. WEBSTER, OF INDEPENDENCE, IOWA

DISPLAY AND SHIPPING DEVICE

Application filed March 15, 1928. Serial No. 261,812.

My invention relates to improvements in display and shipping devices, and the object of my improvement is to supply a device having inexpensive, simple, and effective structural constructions which adapt it for use in the convenient mounting removably thereon of open receptacles for goods, the constructions being such as to strongly reinforce the device against crushing strains due to transportation or otherwise.

I have accomplished this object by the means such as are exemplified in the devices described and claimed herein, and which are illustrated in the accompanying drawings, in which Fig. 1 is a vertical longitudinal section of one of my said devices and Fig. 2 is a rear elevation thereof, while Fig. 3 is a front elevation thereof. Figs. 4 to 6 inclusive are plans of the intermediate container structures of the device of said Fig. 1 as spread out in flat planes respectively. Fig. 7 is a vertical longitudinal section of a modified device, and Fig. 8 is a front elevation thereof.

It is to be understood that other modifications of my device may be made without departing from the principles of my invention or the scope of its claim.

The device of Fig. 1 has a pair of spaced vertically disposed side wall standards 1 having their front edges stepped slopingly. These standards are rigidly connected by relatively superposed and slopingly stepped elements indicated by the characters A, B and C respectively the rear parts of the elements B and C being preferably positioned below the element A, the element B being extended under the forward part of the element A, and the element C being extended under the forward part of the element B to save room and material in construction and for convenience in shipping or on display.

The uppermost element A is a characteristic feature of my invention as to its structural reinforcements at its opposite front and rear ends which materially strengthen the

device against transverse crushing strains. This element A is a single plate of a bendable material, such as plain or corrugated fiber board, and shown in plan in Fig. 4 wherein the plurality of transverse dotted lines indicate creases made across the board to locate transverse bends.

This element A is bodily of rectangular shape with side flaps numbered 6, 13, 12, 11 and 14 on opposite sides. The middle body part 2 provides the bottom of the upper container A, and the bendings of the plate at the rear provide parts 3, 4 and 5 which with a securing end flap 7 cemented on the bottom part make a hollow triangular cross sectional reinforcing structure, the side flaps 6 being bent over on the side dotted lines or creases and cemented upon the inner walls of the standards 1. The forward end part of the element A is similarly shaped into a triangular reinforcing or stiffening structure from the parts 8, 9 and 10 with like side flaps 11 cemented also to the standards. The opposite side flaps 13, 12 and 14 are bent upwardly along the side creases and cemented also to the standards. Paper sealing strips may be used to line the angular inner parts of the open top container A thus formed if desired and to further reinforce the device.

One or more containers of the kind shown at A may be used in the device, but I have shown in the lower containers B and C modifications as follows. The container B is shown in plan in Fig. 5, being a flat plate transversely and longitudinally creased in different places and its parts bent so that the main part 18 becomes the bottom of the container B, open at the rear, but closed in front by a triangular section structure formed by the parts 19, 20 and 21 and side flaps 22, 23 which latter are like the long side flaps 23 cemented to the standards 1. The part 21 overlies the bottom part 18.

The lowermost container C is displayed in plan in Fig. 6, wherein 29 provides the bot-

tom of the container likewise open at the rear end below the container B, and the parts 26, 27 and 24 provide the forward triangular section structure with triangular side flaps 28, and the rectangular side flaps 31 and 30 all cemented upon the standards 1. The part 24, however, underlies said triangular section front structure and the bottom part 29, and at a transverse hinging crease a terminal part 25 is bent downwardly and is free at its side edges from the standards to supply a vertical prop for the device which can be swung against the part 24 when the rear corner parts of the standards 1 are collapsed inwardly along creases, to contract the device for packing and shipping.

The numerals 15, 16 and 17 denote like open top receptacles, adapted to contain packages of gum, confections, or other packed goods, and to be displayed upon the device, fitting removably into the hollows of the containers A, B and C respectively. When emptied, the receptacles may be removed and replaced with filled ones. In order to permit the seating of the receptacles in the lower containers B and C, the rear ends are left open, to receive them slidably thereinto, there not being convenient access thereto from the front.

In the modified device of said Figs. 7 and 8 a like principle of construction is used as in the uppermost container A of said Fig. 1, in providing triangular section reinforcing structures at the front and rear ends. This device has the spaced side standards 31 to whose inner walls the side flaps 47, 43, 39 and 36 of the plate 42 or bottom part of the device are cemented. The upper rear triangular structure is made up of the parts 34, 35 and 37, while the lower front structure is made up of the parts 46, 45 and 44, the latter continued upwardly in the part 42 cemented to the bottom part 46, and the part 32 extending from the part 34 underlying the part 38 and bent from the latter at a transverse crease to be a depending prop 33 to be used as that described in the first-mentioned device.

The bottom plate may be in parts 42 and 38 in the same plane, the middle part of the element being bent at appropriately located creases to be doubled upwardly into a middle transverse partition 41—40, thus affording two containers to the device. This doubled partition also strengthens the device as against transverse strains or warping.

Having described my invention, what I claim as new, and desire to secure by Letters Patent, is:

In a device of the character described, spaced side standards, and a plurality of elements secured therebetween in superposed stepped relation and shaped to provide open top containers for removably fitting receptacles, the uppermost element having front

and rear reinforced walls, and the elements below having reinforced front walls and being open at the rear to receive and discharge fitting receptacles therefor, the forward parts of the lower elements as containers opening upwardly in advance of each other and the 70 uppermost container for display of goods mounted in the containers and removable receptacles fitted in said containers.

In testimony whereof I affix my signature. 75
